CLAIM

The ornamental design for a lid for surgical bur kit holder as shown and described.

DESCRIPTION

FIG. 1 is perspective view of a lid for surgical bur kit holder according to the present invention;

FIG. 2 is a front elevation view of the lid for surgical bur kit holder;

FIG. 3 is a right side elevation view of the lid for surgical bur kit holder;

FIG. 4 is a left side elevation view of the lid for surgical bur kit holder;

FIG. 5 is a rear elevation view of the lid for surgical bur kit holder;

FIG. 6 is a top plan view of the lid for surgical bur kit holder; and,

FIG. 7 is a bottom plan view of the lid for surgical bur kit holder.

1 Claim, 7 Drawing Sheets
